Primary Examiner — Karen E Kearney*Assistant Examiner* — Haley K Schnebele*(74) Attorney, Agent, or Firm* — Heedong Chae; Lucem, PC(57) **CLAIM**

The ornamental design for a pump head for cosmetic container as shown and described.

DESCRIPTION

FIG. 1 is a perspective view of a pump head for cosmetic container showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a top rear perspective view thereof; and,

FIG. 9 is an exploded perspective view thereof.

The broken lines depict portions of the pump head for cosmetic container that form no part of the claim.

1 Claim, 6 Drawing Sheets(56)
